by his Atty
I. M. Munro Fennick & Company

UNITED STATES PATENT OFFICE.

FRANK B. MALLORY, OF ORANGE, NEW JERSEY.

SHUTTER-WORKER.

SPECIFICATION forming part of Letters Patent No. 340,798, dated April 27, 1886.

Application filed January 27, 1886. Serial No. 189,931. (No model.)

To all whom it may concern:

Be it known that I, FRANK B. MALLORY, a citizen of the United States, residing at Orange, in the county of Essex and State of New Jersey, have invented certain new and useful Improvements in Shutter-Workers; and I do hereby declare the following to be a full, clear, and exact description of the invention, such as will enable others skilled in the art to which it appertains to make and use the same.

In the accompanying drawings, Figure 1 is a perspective view of a portion of a window-frame and one shutter with my improvement. Fig. 2 is a vertical section through the wall of a building, and showing my improvement applied. Fig. 3 is a vertical section through the worm and its shaft, also showing in elevation the worm-wheel, its journals, and the housing-box of my invention. Figs. 4 are perspective views of the two parts of the worm and worm-wheel inclosing housing. Fig. 5 is a horizontal section in the line $x-x$ of Fig. 3. Fig. 6 is a detail view of the guideway of the lever-arm made to travel therein in the act of opening or closing the shutter. Fig. 7 is a cross-section in the line $y-y$ of Fig. 2, showing the two-part extension-shaft. Fig. 8 is a detail view of the detent for holding the shutter either open or closed. Fig. 9 is a modification of the construction of the two-part extension-shaft, and illustrating the application of speed-gearing thereto. Fig. 10 is a modification of the two-part extension-shaft, and Figs. 11 are end views of said modification; and Fig. 12 is a side view of a portion of the finished two-part extension-shaft, the shoulder on its inner end being formed by a metal ring seated in a groove, same as in Fig. 10.

My invention has for its object to improve, simplify, and cheapen the construction of shutter-workers, whereby the same can be more readily and quickly applied, thereby saving time as well as greatly reducing the cost of attaching shutter-operating devices.

In Fig. 1 of the drawings I have shown a shutter, A, hinged to its frame A', and with improved shutter-worker B applied to the frame about midway of its length, and so as to have its lever-arm a engage with the shutter at a point midway of its length, and to this end I secure a guideway, a' , to the middle rail, a^2 , of the shutter, said guideway being cast with a flat plate, as a^3 , at one end, and

adapted to be screwed to the rail a^2 , as shown, and with its body portion having a groove, as b , throughout its length on its under side, wherein the bent-up end b' of the lever-arm a travels during the act of opening and closing the shutter.

Fig. 2 shows my improved shutter-worker in working position with the frame A', the same consisting of a main square shaft, c , having its outer end formed or provided with a worm, c' , upon its enlarged cylindrical portion c^2 , which, at either end, is formed with shoulders, as e e' , and with reduced cylindrical journals, as at $e' e^2$, so that when in place in the housing-box D (shown in said figure) the journals $e' e^2$ will have support in the front and rear plate of said box D, as shown, the shoulders e serving to prevent longitudinal displacement of the worm-shaft c . This worm-shaft at its inner end is made to enter a long square socket of a handle-shaft, d , provided with a handle, d' , to revolve the same, the handle-shaft being made to pass through and have a proper bearing in a plate, d^2 , secured to the inside of the frame A', and supplied with a hinged detent, as d^3 , (shown clearly in Fig. 8,) to engage in an opening or slot, d^4 , in the hub of the handle d' , and thereby, when desired, prevent the shutter-worker from being operated.

It will thus be seen that one of the elements of my shutter-worker may, when necessary, consist of a two-part extension-shaft which admits either of a contraction or an extension of the effective length of the same when combined as shown, thereby readily adapting the shutter-worker to be applied to walls of variant thickness, as well as shutter-frames having side pieces of variant widths, and that to facilitate its application for use I provide said extension-shaft with a housing of peculiar construction, and which is at once simple, cheap, and exactly adapted to receive and hold in place the worm c' and its worm-gear w . (Shown in Fig. 3.)

The housing D, as clearly represented in Fig. 4, consists of two main parts, as F and F' in said figure. As delineated in Fig. 4, the part F as a whole consists of one homogeneous mass of metal cast with a back plate, g , a projecting weather-guard, g' , which, however, may be omitted as not indispensable, and two projecting journal-bearings, $g^2 g^3$, while a circular per-

foration, as e' , serves as an opening through which the shaft c may be inserted into position, as shown in Fig. 2, and therein have a bearing for its journal e' . Part F is also provided with elongated apertures, as $i' i''$, into which, respectively, the riveting dowels or projections $j' j''$ are made to enter when the parts F and F' are brought into juxtaposition, as in Figs. 2 and 3, and together secured by riveting, as signified at j^3 . Instead of these elongated openings $i' i''$, round holes may be employed to receive one or more pintles in lieu of the riveting projections $j' j''$, said plate also having screw-holes, as shown, by which to secure it in place, as in Fig. 2.

The part F' (shown in Fig. 4) is made in box form with five sides, mostly closed, as shown, and with spaces, as $v' v'$, through its top and bottom walls, to receive with exactness the journal-bearings $g^2 g^3$ when the parts F and F' are secured in juxtaposition, as in Figs. 2 and 3, said spaces terminating, as shown, in journal-bearing half-seats $t t$ in said top and bottom walls, to correspond with like half-seats, $t' t'$, in the journal-bearings $g^2 g^3$ of part F, and so form a complete journal-bearing seat for the journals $t^3 t^4$ of the worm-gear w when said gear, with its lever-arm a , is in working position, as shown in Fig. 3, and in which position the ends of the worm-gear cylinder w' respectively abut against the under surface of the journal-bearing g^2 and the upper surface of the journal-bearing g^3 , and thus prevent displacement of the worm-gear when in working position, as shown in Figs. 2 and 3.

By thus constructing the two-part housing D my shutter-worker may be readily adjusted into working position, as indicated in Fig. 2, by first passing the shaft c through the back plate, g , with the shoulder e of the worm-cylinder c^2 abutting against the back plate, g , of the part F. This having been done, the worm-gear w is then set with its journals t^3 and t^4 into the half journal-seats $t' t'$ of the part F, as shown in Fig. 3. This done, the metal boxing F' is now brought up against the metal part F, the journal-bearings $g^2 g^3$ of the part F entering the spaces $v' v'$ of the part F' and the projections $j' j''$ entering the apertures $i' i''$ of said parts, while at the same time the journal e^4 of the worm c' will pass through the opening e^4 of the part F', and so have a proper journal-support, and in which position the several parts are maintained in fixed place by the riveting at j^3 , as indicated in Fig. 2.

By applying the shutter-worker above the sill G and midway of the shutter, A, to be worked, I not only so locate it as to be out of the way while manipulating curtains which may be at the window on the inside, but also out of reach of meddlesome persons, while at the same time, by having the power of the lever a act midway of the shutter to open and close it, the leverage-power is exerted upon the shutter at the center of resistance, and thus the shutter is moved without liability

of torsional strains upon the shutter and the parts during such act.

I have shown in Fig. 9 two spur-gear wheels, H H', one being on the handle-shaft d and the other on a pin of the handle d' , and the whole supported in a metal bracket, H^2 . By this gearing the speed of the worm can be increased. I have also shown in same view the socketed portion of the handle-shaft d , constructed in longitudinal halves and held together by a tube, H^3 . These halves are connected to a collared portion, H^4 , of the handle-shaft d .

In Figs. 10, 11, and 12 I have shown the handle-shaft d with a shoulder, I, formed by inserting a wire ring into a groove of said shaft. I also have shown the shaft as cast of malleable iron and with a turned-up lip, I', which lip can be turned down, as shown in Fig. 11, after the handle-shaft has been cast, and by this means the shaft may be cast without a core at its end I².

I would state that when the weather-guard g' is used it serves its ordinary purpose of a top guard against ice and snow, and also as a means for keeping the lever-arm a in position, and this would be its function if the shoulders $w' w'$ of the worm-wheel were left off.

I contemplate leaving out metal, so as to lighten the housing at such points as may be practicable, and still retain the necessary bearings and connections between the several parts, and therefore do not confine myself to a completely closed housing.

What I claim as my invention is—

1. The combination of the lever-guideway a' attached to the outside of the shutter, lever-arm a , having a vertical journaled portion which enters the housing and turns therein, and horizontal portion having a bent-up end which enters the groove of the lever-guideway and works freely therein, the worm-wheel w , applied between the journals of the lever-arm, the worm-shaft and worm c' , and the housing D, formed of the two parts F F' united, substantially as and for the purpose described.

2. The combination of the part F of the housing D, provided with half bearing-seats $t' t'$ and with riveting-apertures, with the part F', having half bearing-seats $t t$ and riveting projections or pintles, substantially as and for the purpose described.

3. The combination, with the two-part housing D and the lever-arm a , of the weather-guard g' , applied to the part F of the housing and acting as a guard, and also serving to keep the journaled end of the lever-arm in position in the housing, substantially as described.

In testimony whereof I affix my signature in presence of two witnesses.

FRANK B. MALLORY.
